STOVE

John E. Chambers, Shelbyville, Ind.

Application September 20, 1937, Serial No. 164,675

3 Claims. (Cl. 236—32)

It is the object of my invention to provide a gas range with means for automatically controlling the supply of gas to a burner on the cooking top for the purpose of maintaining a constant predetermined temperature in a vessel disposed above such burner. More specifically, it is my object to attach permanently to a gas range a temperature-responsive element which can readily be moved into a vessel disposed on the cooking top and which can, when desired, be withdrawn from such vessel when it is desired to remove the vessel from the cooking top. Another object of my invention is to provide a temperature-responsive element which, while readily insertable into any vessel disposed above its associated burner, can be moved to an inoperative position when not desired, so that it will not interfere with free use of its associated burner.

In carrying out my invention I mount above the burner which is to be automatically controlled a pivoted carrier which bears the temperature-responsive element of the automatic controlling mechanism. The axis of pivotal mounting of this carrier is disposed at a considerable distance above the cooking top, so that when the carrier is swung into a horizontal position extending outwardly from its axis of pivotal mounting the distance between it and the cooking top will be considerably greater than the height of the largest vessel or utensil ordinarily associated with the range. The carrier is made long enough so that when swung downwardly from its raised position into a vessel placed on the associated burner the temperature-responsive element will be disposed near the bottom of such vessel. The temperature-responsive element which I prefer to use is in the form of a bulb containing an expansible fluid and connected through a small-diameter tube of flexible material to a pressure-responsive element controlling the valve which regulates the supply of gas to the associated burner. In order to avoid excessive flexing of this tube when the carrier is moved from one position to another, the tube may be formed into a helical coil concentric with the axis of carrier movement, and such coil may be loosely supported by a spool-like element disposed within it.

The accompanying drawing illustrates my invention: Fig. 1 is an end elevation of a portion of a gas range showing a vessel disposed on the cooking top and the temperature-responsive element located in such vessel, some of the parts shown being broken away to appear in cross-section; Fig. 2 is a front elevation of the con-

struction illustrated in Fig. 1, again with parts broken away and shown in section; and Fig. 3 is a fragmental plan view of the vessel showing the temperature-responsive element in place

5

In the drawing, the gas range is shown as embodying a cooking top 11 having a vessel-supporting grid 12 disposed above a burner 13. Desirably, any burner with which my invention is associated is disposed at the rear of the cooking top adjacent the conventional back-splasher 14, which may then be employed as a support for the automatic regulating mechanism.

The automatic regulating mechanism 15 illustrated in the drawing is of a conventional type. It embodies a main valve 16 controlling the supply of gas from a supply line 17 and having a control handle 18. A pressure-responsive valve, responsive to pressure in a control line 20 and adjustable by a knob 21, regulates the supply of gas to a conduit 22 extending to the burner 13. Details of the automatic gas-regulating valve are not illustrated, as such devices are well known and the details may vary without departure from my invention.

In embodying my invention in a stove of the type illustrated in the drawing, the automatic regulating mechanism 15 is mounted on the back splasher 13 at a considerable distance above the cooking top 11 and with the control elements 18 and 21 disposed on the front face of the back splasher. Beneath the automatic regulating mechanism, I attach to the front face of the back splasher a U-shaped bracket 25 the two legs of which support a horizontal pivot bolt 26 which provides a pivotal mounting for a carrier 27. The bottom portion 28 of the carrier 27 is desirably tubular and has its lower end closed as indicated in the drawing. Above the tubular portion, the carrier is provided with two parallel ears 29 which overlap the parallel legs of the U-shaped bracket 25 and receive the pivot bolt 26.

The temperature-responsive element which, as indicated above, is desirably a fluid-containing bulb 31, is disposed within the tubular portion 28 of the carrier 27 and has connected to it a small diameter tube 32 of flexible material. Desirably, the upper end of the tubular portion 28 of the carrier is provided with a stopper 33 having a central hole through which the tube 32 passes. Above the stopper 33, the tube 32 is formed into a helical coil about the axis of the pivot bolt 26, such coil desirably having several turns and being supported by a spool 34 held in place in the brack-

et 25 by the pivot bolt 26. Beyond this helically coiled portion, the tube 32 extends to the pressure-responsive element of the automatic regulating mechanism 15.

5. In order that the carrier 27 may remain in any position of adjustment to which it has been moved, I prefer to associate with it a friction-brake means yieldingly opposing its rotation about the axis of the bolt 26. For this purpose, the bolt 10 26 extends outwardly at each end beyond the adjacent ear 29 of the carrier 27 and is there provided with a cup-like housing 36 enclosing a compression spring 37 which bears against the adjacent ear 29 and forces it into frictional contact with the adjacent leg of the U-shaped bracket 25.

In the drawing, the carrier 27 is shown as disposed in its operative position, where it extends vertically downward into a vessel 40 supported 20 on the grid 12 above the burner 13. If desired, there may be provided for the vessel 40 a lid 41 having in its edge a cut-away portion 42 providing a notch through which the tubular portion 28 of the carrier extends. As indicated 25 above, the carrier is of such a length as to extend nearly to the bottom of the vessel 40. Changes in pressure created in the bulb 31 as a result of changes in temperature of the contents of the vessel 40 will be transmitted through the tube 32 to the automatic regulating mechanism 15 and will serve to effect the desired control of 30 the quantity of gas supplied to the burner 13 through the conduit 22. When it is desired to

remove the vessel 40, the lid 41, if in place, is withdrawn and the carrier 27 swung about the axis of the bolt 26 to the dotted-line position indicated in Fig. 1. In this position, the carrier is well above the top of the vessel 40 which can then readily be removed. Because of the formation of the tube 32 into a helical coil, any unit displacement thereof created by swinging movement of the carrier 27 is relatively slight, and the tube sustains no injury. 10

I claim as my invention:

1. In a gas range having a cooking top and a burner located therebelow, a back splasher projecting upwardly from said cooking top adjacent said burner, a member pivotally attached to said back splasher on a horizontal axis above said burner, pressure-responsive means for controlling the supply of fuel to said burner, a fluid-containing bulb mounted on said member near the free end thereof, and a tube of flexible material connecting said bulb with said pressure-responsive means, said tube including a portion formed into a helical coil coaxial with the pivotal mounting of said member. 15

2. The invention set forth in claim 1 with the addition of means disposed within the helically coiled portion of said tube for supporting it. 20

3. The invention set forth in claim 1 with the addition of friction-brake means for yieldingly holding said member in any position throughout 30 its range of movement about its axis of pivotal mounting.

JOHN E. CHAMBERS.
